UNITED STATES PATENT OFFICE.

ABRAHAM B. COHEN, OF FAR ROCKAWAY, NEW YORK.

TOOTH-CLEANING DEVICE.

1,421,911.

Specification of Letters Patent.

Patented July 4, 1922.

Application filed August 22, 1918, Serial No. 250,928. Renewed April 21, 1922. Serial No. 555,918.

To all whom it may concern:

Be it known that I, ABRAHAM B. COHEN, a citizen of the United States, residing at Far Rockaway, in the county of Queens and State of New York, have invented, certain new and useful Improvements in Tooth-Cleaning Devices, of which the following is a specification.

This invention relates to tooth cleaning devices and more particularly to that class of tooth cleaning devices in which the cleaning surface touching the teeth and gums may be renewed at each cleaning operation.

It has more particularly for its object to provide a tooth cleaning implement and auxiliary means employed therewith which will be economical to manufacture, which will provide a tooth cleaning material which may be thrown away after each operation, and which will be superior in its action to the ordinary bristle tooth brush.

In the drawings,

Figure 1 is a perspective view of the tooth cleaning roll together with the implement by which it is applied,

Figure 2 is a sectional view of the tooth cleaning roll alone,

Figure 3 is a perspective view of another form of the tooth cleaning device, and

Figure 4 is a slightly different embodiment of an impregnated fabric for cleaning the teeth shown in Figure 3.

In Figure 1, 1 represents the tooth cleaning roll or device and 2 the implement by which it is applied to the teeth. 3 is the handle of the implement carrying the spring shank 4 and the tubular sleeve 5 which enables the roll 1 to be attached or detached from the implement.

Figure 2 represents a sectional view of the roll 1 which roll consists essentially of soft cotton 7 having a thin facing 10 of non-absorbent cotton as shown. This non-absorbent cotton itself, which is inherently harder than the absorbent cotton, is made up into sheets which are rolled into spirals and are sold in all drug stores and many other places throughout the country.

To make the compound strip shown in the drawings, it is only necessary to take a sheet of the absorbent cotton, put a sheet of the non-absorbent cotton on top of it, and a gentle pressure is sufficient to unite them, so

that the compound sheet can be formed into a roll. The fibres of the one cling frictionally to those of the other for this purpose. This roll for the purposes of use as a tooth cleaning device is impregnated with a dentifrice, the particles of which, shown in the drawing, are noted as 6. A suitable dentifrice for this purpose is made of lactose, 55 menthol, carbolic acid, pulverized castile soap and magnesium peroxide, all finely powdered, to which mixture ethyl alcohol is added so as to secure a semi-liquid emulsion. 60 This emulsion is used for impregnating these cotton rolls. The alcohol contained in the fluid mixture evaporates leaving the solid constituents deposited in the cotton. Since absorbent cotton has such fine 65 pores as to prevent even the finer particles from penetrating therein, even when the absorbent cotton has absorbed a liquid, it has not been hitherto thought possible to drive particles of a solid dentifrice into the pores 70 by means of the entraining action of an emulsion such as above described. The said emulsion however enlarges the pores of the cotton sufficiently so as to enable the solid particles to be deposited therein. It will be 75 evident that this mixture of lactose, menthol, carbolic acid, soap and magnesium peroxide remaining distributed in the pores of the cotton is a very efficient antiseptic and tooth cleaning agent. The rolls are 80 used with the implement shown in Figure 1, each roll of the impregnated fabric having the particles 6 of the dentifrice at and near its periphery.

Figure 3 shows a sheet of cotton 7 to which 90 the dentifrice 6 in semi-fluid form has also been applied. This sheet has perforations 9 permitting a small portion of the cotton to be detached each time. Each portion of the fabric is then formed into a roll. 95

Figure 4 shows a modification of the sheet of Figure 3 in which the dentifrice 6 is applied to only one surface of the sheet of cotton and the sheet is not entirely impregnated with the dentifrice. When a piece of 100 the fabric shown in Fig. 4 is formed into a roll, the impregnated layer must be at the periphery of the roll. Of course, if the entire fabric has been impregnated, the dentifrice will be distributed in all parts thereof. 105

It will be evident that other dentifrices

can be substituted for the particular compound here shown as these rolls can be treated with any dentifrice which will have a properly antiseptic and detergent effect upon 5 the teeth.

The use of these rolls is preferable to the use of the tooth brush in that the cotton is soft and soothing to the gums and its pliability enables the dentifrice to be carried to 10 all portions of the teeth and gums and none of the unfavorable action on the teeth and gums caused by the hard bristles of the tooth brush is present with the use of this tooth cleaning device. To clean the teeth the roll 15 1, held as shown in Fig. 1, is dipped into water and then rubbed over the teeth, being used in exactly the same manner as if it were the bristle portion of an ordinary tooth brush. If the impregnated fabric has been 20 covered with a thin layer of non-absorbent cotton, this is soon rubbed away by the brushing action, so that the dentifrice can exert its desired action.

The roll 1 provides a convenient means of 25 securing a fresh and uncontaminated supply of dentifrice each time the teeth are to be cleaned. The non-absorbent cotton enables the sheet to hold its shape.

I make no particular claim to the form of 30 implement shown as it is obvious that other

forms of holders can be devised for using these rolls.

What I claim is:—

1. A tooth cleanser comprising a composite sheet composed of an interior soft 35 absorbent cotton and a facing composed of a fabric which does not substantially swell up when moistened, the said soft absorbent cotton having pores containing particles of solid dentifrice.

2. As an article of manufacture, a tooth cleaning device including a composite sheet having one face of soft absorbent fabric, and another face of non-absorbent fabric, the first-named fabric being impregnated 45 with a dentifrice, which is distributed in the pores thereof.

3. As an article of manufacture, a tooth cleaning device including a composite sheet having one face of soft absorbent cotton and 50 another face of non-absorbent fabric, the said absorbent cotton having enlarged pores and being impregnated with a dentifrice, which is distributed in the pores thereof, the said fabric being of a character to 55 hold said absorbent cotton in shape.

In testimony whereof I hereunto affix my signature.

ABRAHAM B. COHEN.
